FLASH LAMP

Michael J. Neumann de Margitta, Budapest,
Hungary, assignor to Westinghouse Electric &
Manufacturing Company, a corporation of
Pennsylvania

Application October 6, 1939, Serial No. 298,276
In Hungary August 19, 1939

3 Claims. (Cl. 67—31)

The invention relates to lamps and especially to flash lamps used in photography.

An object of the invention is to make safe the use of photographic flash lamps.

Another object of the invention is to eliminate any dangerous bulb explosion from flash lamps.

Another object of the invention is to provide a flash lamp which can be conveniently carried with a large number of other lamps.

A still further object is to eliminate glass in the construction of photoflash lamps.

A still further object is to provide a simplified structure that can be easily assembled, quickly utilized, and readily disposed of.

Other objects and advantages will be apparent from the following description and drawing in which:

The figure is a view in elevation with a portion of the wall broken away of a preferred embodiment of a flash lamp constructed according to the invention.

As stated above, certain objects of my invention are to eliminate glass from the construction of the photoflash lamp, and to provide an easily assembled and utilized device that can conveniently be carried in large numbers.

I accomplish these objects by making the container of a flash lamp of organic material of suitable light translucency or transparency with adequate elastic and plastic properties. These materials comprise one or more of the class designated as plastic materials. These plastics preferably have a softening point somewhere between 150° and 300° F., and also a heat capacity, heat transfer and heat conductivity and dissipation so that there will be no explosion of the material.

The preferred plastic is that of cellulose acetate. Although the transparent or translucent plastics of the various resins such as phenol-formaldehyde may be used. Some of the suitable plastics are sold under the tradenames of "Lucite," "Plastacel," "Plexi-Glas," or "Bakelite BT-48-005."

In the drawing, I have disclosed a preferred embodiment of my invention in which the container 10 preferably comprises a tubular member with an integral closed end 11. This tubular container is preferably of cellulose acetate which I have found to be especially adapted from among the various plastics for photoflash work. The open end 12 of this tubular casing is closed by a base 13 also of plastic material and especially cellulose acetate. This base 13 preferably has a

dish shape curving downward to a bottom portion at 14. The edge of the dish-shaped base has a flange 15 to make suitable closure contact with the edge 12 of the tubular casing 10. The adjoining edges 12 and 15 may be connected together either by welding or cementing. In welding, the parts are pressed together and heating them partially at least to raise the temperature of the parts so as to soften and mold them together. Various suitable cements may be utilized including the applications of solvents and polymerizing liquids. In cementing, mechanical or gas pressure as well as the help of some heating may be utilized as desired.

15 The envelope has a filling 16 of the usual combustible material mass filling used as the flash element in an oxygen atmosphere. Also within the envelope, at any suitable location, is the igniting means 17 for the combustible material mass 16.

20 The particular embodiment illustrated provides a very easily assembled and utilized form of electrical connections to the igniting means 17. On the underside 14 of the dish-shaped base is an integral extension or stem 18 of cellulose acetate. A connection 19 from one end of the igniting means 17 passes through the base and through the extension 18 and terminates at a contact metal bulb 20 at the end of the extension 18. Surrounding the projection 18 is a metal ring 21 that is insulatingly spaced from the contact bulb 20 by the intervening cellulose acetate. The contact ring 21 has a connection 22 extending through the base 13 to the other end of the igniting means 17. The type of socket for making connections to the ring 21 and bulb 20 is, of course, well known in the electrical art.

25 It is apparent that many other forms of plastic photoflash lamps might be constructed and many of those which I originally disclosed in this application have been divided out and described in the following continuations or continuations in part:

30 Ser. #302,023, filed October 30, 1939, and Ser. #315,738, 315,739, 315,740, 315,741, 315,742, 315,743, 315,744, filed January 26, 1940.

35 I claim:

1. A flashlamp comprising an envelope including a base portion of self-supporting cellulose acetate, a combustible metal, an active gas and igniting means in said envelope, an integral outward extension on said base, an electrical connection from said igniting means extending through said integral extension, an electrical contact member on the end of said integral ex-

tension making contact with said electrical connection, a second contact member supported on said integral extension and insulatingly spaced from said first mentioned contact member by said cellulose acetate, and an electrical connection from said second contact member extending through the cellulose acetate to said igniting means.

2. A flashlamp comprising an envelope closed by a dish-shaped base of self-supporting cellulose acetate, a combustible metal, an active gas and igniting means in said envelope, an integral extension of cellulose acetate on the underside of said dish-shaped base, a connection from said igniting means extending through said extension and an electrical contact member on the end of

said extension and connected to said connection, a second contact member supported on said extension and a second connection passing through said base to said igniting means.

5 3. A flashlamp comprising a tubular casing of self-supporting cellulose acetate with an integral closed end, a dish-shaped base of self-supporting cellulose acetate closing the open end of said tubular casing, an integral extension of cellulose acetate on the underside of said base, a metal band on said extension, a metal tip on the end of said extension, a combustible metal, an active gas and igniting means enclosed by said casing and base, and electrical connections extending from 10 15 said igniting means to said band and tip.

MICHAEL J. NEUMANN DE MARGITTA.
